Primary Examiner — Paula Allen Greene

(57) **CLAIM**

The ornamental design for headset, as shown and described.

DESCRIPTION

1. Headset
- 1.1 : Front
- 1.2 : Back
- 1.3 : Top
- 1.4 : Bottom
- 1.5 : Left
- 1.6 : Right
- 1.7: Right Perspective
- 1.8: Left Perspective
